MICROFICHE READER

Arnis Edward Peters, La Crosse, Wis., assignor to
Microcard Corporation

Filed July 23, 1965, Ser. No. 86,269

Term of patent 14 years

(Cl. D61—1)

FIG. 1 is a front perspective view of a microfiche reader, showing my new design;

FIG. 2 is a top plan view thereof;

FIG. 3 is a left-side elevational view thereof;

FIG. 4 is a front elevational view thereof;

FIG. 5 is a right-side elevational view thereof, partially in section as indicated by line 5-5 in FIG. 4; and

FIG. 6 is a rear elevational view thereof.

The essential features of my design are shown in full lines in the drawings. The broken-line structure in FIGS. 3 through 6 is omitted from FIGS. 1 and 2 for convenience of illustration.

I claim:

The ornamental design for a microfiche reader, substantially as shown and described.
